COMBINED ASHTRAY AND SNUFFER

Edward C. Moulton, Newburgh, N. Y.

Application April 28, 1936, Serial No. 76,855

1 Claim. (Cl. 131—51)

The invention relates to a combined ash tray and snuffer and more especially to an extinguisher or snuffer for a lighted cigarette.

The primary object of the invention is the provision of an extinguisher or snuffer of this character, wherein the same is so constructed that when a lighted cigarette is inserted therein it can be readily and easily extinguished or snuffed out and when such snuffer or extinguisher is carried by an ash tray the edges or charred end of the cigarette can be injected into the tray for deposit therein without liability of setting fire or burning of the deposit within the tray, as for example, portions of cigarettes thrown therein 15 when discarded after the smoking thereof.

Another object of the invention is the provision of an extinguisher or snuffer of this character, wherein the same is novel in construction and is adaptable to become a part of an ash tray 20 or is capable of being mounted within an automobile or other vehicle for service as an extinguisher or snuffer for use by smokers.

A further object of the invention is the provision of an extinguisher or snuffer of this character, which is simple in its construction, thoroughly reliable and efficient in its operation, readily and easily operated, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a perspective view of an ash tray showing the extinguisher or snuffer constructed in accordance with the invention built therein.

Figure 2 is a top plan view.

Figure 3 is a vertical sectional view thereof.

Figure 4 is a vertical sectional view through the extinguisher or snuffer removed from the tray.

Figure 5 is an elevation of a modified form.

Figure 6 is a face view of the turning knob of the snuffer or extinguisher.

Similar reference characters indicate corresponding parts throughout the several views in the drawing.

Referring to the drawing in detail, particularly Figures 1 to 4 inclusive, A designates generally an ash tray which may be of conventional kind and in this instance is made from glass although 55 it may be made from any other suitable mate-

rial and has disposed at its open top distributed along the rim 10 thereof cigarette holders 11, these being conventional while molded or otherwise built in the body of the tray A is an extinguisher or snuffer as will be hereinafter fully 5 described.

This extinguisher or snuffer comprises a barrel 12 preferably made from metal having an upwardly curving or rolled edge 14, while within the barrel 12 is a coiled wire 15, one convolution at 16 being opened at one side of the coil to a greater extent than the remaining coils of this wire.

The coil of wire 15 at the end 17 is made fixed 15 to a turning knob 18 rotatably fitted at 19 in the outer end of the barrel 12 and this coil of wire 15 is so located to have the coil 16 in confronting relation to the mouth 13 for a purpose presently described.

In building the extinguisher or snuffer in the body of the tray A the barrel is disposed horizontally while the mouth 17 protrudes upwardly through the rim so that free access can be had to this mouth for the insertion of a cigarette 20 25 within the mouth when lighted to bring the burning end thereof into the coil 16 whereby on the turning of the coiled wire 15 by the knob 18 the said coil 16 will snuff or cut off the burning end of the cigarette for the extinguishing of the 30 lighted end thereof. On further turning of the coil of wire 15 the cut off, extinguished or snuffed end of the cigarette 20 will be discharged into the tray A through the inner open end 21 of the barrel 12 as will be clearly apparent from Figures 35 3 and 4 of the drawing.

In Figure 5 of the drawing there is shown a slight modification wherein the barrel 22 has an externally threaded inner end 23 so that it can be engaged through a suitable opening accommodating this threaded end within the dash or instrument board of a motor vehicle, a portion of the board being indicated at 24, and the extinguisher or snuffer being made fast in position by a lock nut 25 for service within the motor vehicle 45 for extinguishing or snuffing the lighted end of a cigarette.

It is preferable to have the outer face of the knob 18 marked with arrows 26 and 27, respectively, one being indicative of the normal starting 50 position for operating the coil of wire 15 within the barrel 12 and the other the direction of the turning of this coil of wire by manipulating said knob 18.

The extinguisher or snuffer can be a perma-

nent part of an ash tray or may be a separate article and in both instances is serviceable for the purpose hereinbefore set forth.

The normal position of the coil of wire 15 is to have the coil 16 at the open side thereof confront the mouth 13 so that the lighted end of the cigarette can come well within the coil 16 for the extinguishing or snuffing of such end on the turning of the coil of wire 15. On the turning of the coil of wire 15 the coil 16 will entirely remove the lighted end of the cigarette and when the extinguisher or snuffer is built within the ash tray this removed end as within the barrel 12 can be discharged into the body of the ash tray.

What is claimed is:

The combination of a barrel, a knob rotatably fitting one end of said barrel, a mouth extension rising vertically from the barrel and opening therewith for accommodating a lighted cigarette, and a coil of wire fitted within said knob and snugly confined within said barrel for rotation therein by the knob and having a spread turn for bridging the communication between the mouth extension and said barrel for the snuffing of the lighted end of said cigarette when said cigarette is protruded through the mouth extension into the barrel and into the path of the spread turn. 5 10 15
